UNITED STATES PATENT OFFICE.

CHARLES RANDOLPH McMANIS, OF KEOKUK, IOWA.

SAFETY RAILROAD-CAR.

SPECIFICATION forming part of Letters Patent No. 518,854, dated April 24, 1894.

Application filed December 30, 1893. Serial No. 495,206. (No model.)

To all whom it may concern:

Be it known that I, CHARLES RANDOLPH McMANIS, a citizen of the United States, residing at Keokuk, in the county of Lee and 5 State of Iowa, have invented certain new and useful Improvements in Safety Railroad-Cars; and I do hereby declare that the following is a full, clear, and exact description of the same, reference being had to the annexed drawings, 10 making a part of this specification, and to the letters of reference marked thereon.

The present invention has relation to that class of railroad cars adapted for carrying the United States mail, baggage, money, and other 15 valuables, and where it is required to protect the car against sudden attacks by highwaymen and others whose object it is to obtain possession of the valuables.

The invention therefore consists of a car 20 constructed partly or wholly of metal substantially in the manner shown in the drawings and hereinafter described and claimed.

Figure 1 of the drawings represents a car 25 constructed in accordance with my invention, the roof thereof being partly broken away to show the interior; Fig. 2 a horizontal section thereof.

In the accompanying drawings A represents the body of the car which is constructed of 30 suitable metal in any desirable manner, and if preferred may have an outer covering of wood. This covering however is not essential but may be resorted to to give to the car upon the outside a better appearance. The 35 car upon one or both of its sides is provided with compartments B which have two sliding doors C D of any suitable construction and also hinged doors E at one end of the compartments whereby access can be obtained 40 thereto. The doors E are provided with suitable and well known means for rendering them self locking when closed so that they can be only opened from the outside of the compartment and by a person inside of the car.

The doors C D may be constructed in any 45 well known manner whereby they will freely slide in their bearings when opening and closing them, similar to the ordinary sliding doors now in common use. The doors have suitable handles for operating them as shown at 50 a, the handle of the door C extending inwardly from the compartment side so that it can be

opened only by the person located therein, while the handle of the door D extends outward upon the exterior of the compartment 55 so that the door can only be opened from the outside thereof by a person in the car. If preferred suitable means may be provided for locking the sliding doors in a closed position, but this is not considered absolutely necessary, as it would be impossible to open the doors C from the outside of the car, there being no projections thereon to serve as a handle.

At certain places along the line of road where the train would stop to take on baggage or mail matter, especially at night, it is desirable to take every precaution against any sudden attempt on the part of any one to enter the car for the purpose of robbery. To provide against this night attack the compartments with their several doors are especially designed, and when the car stops at any station during the hours of the night in small country towns, the baggage-master or attendant of the mail-car first opens the end door 65 E to pass into the compartment B, after which the door is closed and automatically locks itself from the outside. The person now within the compartment B opens the sliding door 70 C to receive or deliver the mail, baggage, or other valuables, and after closing the sliding door, the same are passed into the car through the door D which is only opened after the door C is closed. When the door C is open to receive or deliver the mail, baggage, or other valuables, the doors D E remain closed 75 so that should any one for the purpose of robbery get as far as the compartment B it would be impossible for them to pass from the compartment into the car as said compartment 80 would be closed upon all sides located within the car and the doors D E could not be opened except by the person within the car and outside of the compartment. In large cities where there is less danger, the doors D may 85 be left open when arriving at the station until the train again starts.)

At each corner of the car is a suitable defense-chamber F which projects out beyond the sides and corner of the car, and is provided with any suitable number of port-holes 90 b, which are closed when not in use by suitable slides G. These chambers may be of any suitable size and shape and are provided

with hinged doors H which may be provided with suitable means for locking them closed. When closed, these doors will exclude the light from the interior of the chambers which 5 would otherwise enter from the lights in the car, thus enabling the person or persons in the chamber to operate better with their rifles through the port-holes.

The car at one or both ends may be provided with a suitable hinged door I through which access may be had thereto, the door or doors having the usual locks operated from the inside.

The end of the car may have a suitable vent 15 tilating opening c which is protected with a shield to prevent bullets or shot entering, said shield being shown in dotted lines, Fig. 1.

Along the upper portion of the car-body A and immediately under the projecting edge 20 of the car-roof K, are a number of windows L provided with thick glass. These windows are either opened or closed by sliding blinds M upon each side of the car, each series of blinds being connected together by transverse 25 bars d at their ends and a central bar e. This central bar has a slot through which projects a hand-lever N hinged or pivoted to a bracket f rigidly connected to the under side of the roof K of the car. Any suitable means may 30 be employed for operating the sliding blinds and any desirable form of blind may be used in place of those shown, and many changes or modifications may be made in the several details of construction without departing 35 from the principle of my invention.

The car in whole or in part may be constructed of boiler iron, steel, or any other metal found best adapted to the purpose, and the several compartments and chambers with 40 their doors may be variously modified and changed in form so long as it comes within ordinary mechanical skill.

Placing the defense-chambers at the corners of the car and projecting them out from the

sides thereof, is deemed of material importance from the fact that a greater range can be obtained with the rifle by the person located in the chamber.

The blinds when adjusted to close the windows will exclude the light which is of itself 50 important when an attack is being made from the outside of the car.

Having now fully described my invention, what I claim as new, and desire to secure by Letters Patent, is—

1. A safety-car having upon its sides suitable windows, and means for covering or exposing the windows to light or darken the interior of the car, consisting of a plurality of blinds connected together and to transverse 60 rods and a central slotted bar, and an operating hand-lever pivoted to a bracket projecting down from the roof of the car, said lever projecting through the slot in the bar whereby the entire number of blinds upon both 65 sides of the car may be operated simultaneously, substantially as and for the purpose set forth.

2. A safety-car provided with defense-chambers located at the corners thereof and having port-holes and slides therefor, compartments located within the car and having doors upon both its sides and at one end, suitable windows upon the sides of the car connected together and to transverse rods and a 70 central slotted bar, and a pivoted hand-lever projecting from the roof of the car and extending down through the slot in the bar, whereby the blinds upon both sides of the car may be operated simultaneously, substantially as and for the purpose specified.

In testimony that I claim the above I have hereunto subscribed my name in the presence of two witnesses.

CHARLES RANDOLPH McMANIS.
